UNITED STATES PATENT OFFICE.

WILLIAM OSTWALD, OF CHICAGO, ILLINOIS, ASSIGNOR TO UNIQUE LAMP & CASTING COMPANY, A COPARTNERSHIP CONSISTING OF HENRY GOODFRIEND, WILLIAM CHRISTENSEN, AND ALFRED E. LARSEN, OF CHICAGO, ILLINOIS.

DESIGN FOR AN ELECTRIC CEILING FIXTURE.

Application filed October 14, 1925. Serial No. 15,121. Term of patent 3½ years.

To all whom it may concern:

Be it known that I, WILLIAM OSTWALD, a citizen of the United States, residing at Chicago, in the county of Cook and State of Illinois, have invented a new, original, and ornamental Design for Electric Ceiling Fixtures, of which the following is a specification, reference being had to the accompanying drawing, forming part thereof.

Figure 1 is a front elevation of the device.

Figure 2 is a partial plan view showing a portion of the ornamentation completed, the remaining portion within the plain outline involving a mere repetition of that portion more completely shown.

I claim,

The ornamental design for an electric ceiling fixture, as shown.

WILLIAM OSTWALD.
